UNITED STATES PATENT OFFICE.

BENJAMIN M. STEELE, OF PEORIA, ILLINOIS, ASSIGNOR TO HART GRAIN WEIGHER CO., OF PEORIA, ILLINOIS, A CORPORATION OF ILLINOIS.

SEEDING-MACHINE.

1,305,500.

Specification of Letters Patent. Patented June 3, 1919.

Application filed February 9, 1917. Serial No. 147,592.

To all whom it may concern:

Be it known that I, BENJAMIN M. STEELE, a citizen of the United States, a resident of Peoria, in the county of Peoria and State of Illinois, have invented new and useful Improvements in Seeding-Machines, of which the following is a specification.

My invention relates to improvements in seeding machines and particularly what is known in this art as end-gate seeders, and the principal object is the provision of a device which is simple and light in construction, providing a low down hopper and having the mechanism balanced on the end-gate.

15 A further object of this invention is the provision of a mechanism having a hopper mounted on the inside of the end-gate with a conveyer leading from the bottom thereof over the top edge of the end-gate to discharge the seed into the chutes which lead to the broadcast distributing fans.

Another object of this invention is the provision of such a mechanism having the plurality of fans driven by means of a flexible and resilient belt or chain from one of the wheels of the vehicle, a friction clutch being interposed for ready control of the operation.

Another object of this invention is the provision in such a mechanism of the hopper, the conveyer, the plurality of distributing fans, the operating means actuated from the wheel of the vehicle and the flexible and resilient belt or chain for driving the distributing fans and the conveyer.

For the accomplishment of the foregoing and such other objects as may hereinafter appear, my invention consists in the construction, combination and arrangement of parts hereinafter described and then sought to be defined in the appended claims, reference being had to the accompanying drawings which show merely for the purpose of illustrative disclosure, a preferred embodiment, as well as modifications, of my invention, it being expressly understood, however, that various changes may be made in practice within the scope of the claims without digressing from my inventive idea.

In the drawings,—

Figure 1 represents a rear end elevation of an end-gate equipped with the mechanism constructed to embody my invention, the clutch being shown in section to facilitate disclosure;

55 Fig. 2 is a vertical cross section taken substantially on line 2—2 of Fig. 1;

Fig. 3 is a top plan view of the mechanism shown in Fig. 1;

Fig. 4 is a detail view illustrating the agitator drive, and

Fig. 5 is a detail view of a modified form of conveyer.

Fig. 6 is a detail view of the belt.

Referring now to the drawings, the numeral 1 designates the end-gate of a wagon or other vehicle upon which the seeding mechanism is mounted. The hopper 2 and conveyer 3 are positioned on the inside of the end-gate while the distributing fans 4 and the operating mechanism therefor, are mounted on the outside of the end-gate.

This operating mechanism includes the shaft 5 having the beveled gear 6 on one end to drive bevel gear 7 on the vertical shaft 8, the gears being mounted in a suitable casting 9 and packed with grease or other hard lubricant to minimize the noise. Mounted on the shaft 5 is the driving and clutching means 10 which includes the sprocket 11 adapted to be driven by chain or belt from the wheel of the vehicle, this sprocket being loosely mounted on said shaft and having the flange or plate member 12 which is positioned opposite a similar flange or plate member 13. The inner faces 14 of these two flange members are inclined and spaced apart to receive the friction plate member 15, the hub 16 of which is secured to the shaft 5 by the set screw 17 or similar means so as to drive said shaft. Collar 18 having groove 19 is slidably mounted on shaft 5 and has the links 20 pivotally connected to the extensions 21 of the clamping cam members 22, which bear against the face of the flange 23 or plate member 13 and to which are pivotally connected the bolts 24 which pass through apertures 25 in said flange members.

12 and 13 having the locking nuts 25 on the ends thereof. The casing 9 is provided with an extension or bracket 26 to which the operating lever 27 is adjustably and pivotally mounted as at 28, the end of the operating lever being forked as at 29 to engage the groove 19 in collar 18. By this means the clutch is controlled so as to cause shaft 5 to be driven. Due to the adjustable mounting 28 of the operating lever 27, the driving and clutching means may be moved bodily on the shaft 5 upon release of the set screw 17 so as to readily line the sprocket 11 up with the corresponding driving element on 15 the wheel or axle of the vehicle.

The vertical shaft 8 and casing 9 are suitably supported by bracket member 30 on the outside of the end-gate and the shaft 8 has the grooved pulley 31 on its lower portion. This pulley is in horizontal alinement with the pulleys 32 for driving the usual broadcast distributing fans 4. These fans and pulleys are mounted in spaced relation on the vertical shafts 33 having the bracket 20 supporting elements 34 and 35 extending outwardly from the plate member 36, the shaft having an anti-friction bearing on the lower bracket 34 and having a countersink 25 at its upper end to receive the set screw 37 at its upper end to receive the set screw 37 30 mounted in the upper bracket 35.

The pulley 38 on the vertical shaft 39 for driving the conveyer 3 is also mounted in alinement with the pulleys 32 and 32 and the flexible and resilient belt or chain 40 fur- 35 nishes the driving means for these pulleys, power of course, being transmitted from the shaft 5 through pulley 31. The belt is preferably of coiled spring construction so as to be resilient to ease the shock of sudden 40 starting and the like and also to provide a roughened surface to insure operative engagement. The belt is arranged so as to drive the distributing fans in opposite directions, as is well understood.

45 The vertical shaft 39 is supported at its lower end on the bracket 41 having the anti-friction bearing and the upper end being supported by bracket 42 which projects from the conveyer housing 43. The upper 50 end of the shaft is provided with the countersink to receive the adjusting set screw 44. Mounted on the upper portion of this shaft 39 is the gear 45 which meshes with the gear 46 on the horizontal shaft 47 which 55 is journaled in the sides of the conveyer housing 43 and is provided with the sprocket 48 therein. A similar shaft and sprocket construction 49 is provided in the boot or lower portion 50 of the conveyer. 60 Chain 51 having the buckets or flights 52, is operated by said sprockets so as to convey the seed from the boot of the conveyer up to the discharge opening in the head 53. The seed is discharged into the chutes

54 which diverge and extend downwardly to 65 the openings 55 in the baffle or guard plate 56 so that the seed is delivered onto the fans for distribution.

The hopper 2 is provided in its lower portion with the partition 57 which has 70 sides diverging downwardly from the apex 58 so as to direct the seed on opposite sides of the lowermost sprocket in the boot of the conveyer. The controlling slides or gates 59 are slidably mounted in the lower 75 portion of the hopper so as to control the quantity of seed discharged therefrom. The conveyer housing is provided with the bracket members 60 which have the right angled plate portions 59 through which the 80 securing bolts pass, these bolts also passing through the plate, members 36 on the outside of the end-gate.

I also use an agitator 62 mounted in the bottom of the hopper, which agitator may 85 be driven by the belt and sprocket connection 63 from the lower end of the conveyer, as indicated in Fig. 4. The shaft and sprocket construction 49 in the boot of the conveyer is provided with the usual adjusting or tightening means, 64 as indicated in 90 Fig. 4 of the drawing.

As shown in Fig. 5, I may use another form of conveyer instead of the flight conveyer shown in Fig. 2 of the drawing. In 95 this figure of the drawing, I disclose a spiral conveyer 65 driven by means of the skew gears 66 from the vertical shaft 39.

It is seen, therefore, that I have provided a mechanism which is simple in construction and operation, which is exceedingly light, which is balanced on the end-gate and in which the hopper is located in a low-down position. Further than that, the interposition of the friction clutch member 100 105 and the use of the resilient drive provide efficient means for preventing breakage of the parts or injury to the mechanism.

What I claim is:—

1. In combination with an end-gate, a 110 hopper mounted on the inside thereof, a conveyer receiving the discharge from the hopper and discharging over the top of the end-gate, distributing fans on the outside of the end-gate, means for conveying the discharge of the conveyer to said fans, and means for driving said fans and conveyer.

2. In combination with an end-gate, a 120 hopper mounted on the inside thereof, a conveyer receiving the discharge from the hopper and discharging over the top of the end-gate, distributing fans on the outside of the end-gate, means for conveying the discharge of the conveyer to said fans, 125 means for driving said fans and conveyer, said means including a member adapted to be driven from the wheel of a vehicle, and

a clutch mechanism interposed between said member and said fans.

3. In combination with an end-gate, a hopper mounted on the inside thereof, a conveyer receiving the discharge from the hopper and discharging over the top of the end-gate, distributing fans on the outside of the end-gate, means for conveying the discharge of the conveyer to said fans, means 10 for driving said fans and conveyer, said means including a member adapted to be driven from the wheel of a vehicle, and a resilient member for driving said fans and conveyer.

15 4. In combination with an end-gate, a hopper mounted on the inside thereof, a conveyer receiving the discharge from the hopper and discharging over the top of the end-gate, distributing fans on the outside 20 of the end-gate, means for conveying the discharge of the conveyer to said fans, means for driving said fans and conveyer, said means including a member adapted to be driven from the wheel of a vehicle, a resilient member for driving said fans and conveyer, and a friction clutch interposed 25 between said member and said resilient member.

5. In combination with an end-gate, a hopper mounted on the inside thereof, a conveyer receiving the discharge from the hopper and discharging from the top of the end-gate a plurality of distributing fans located in spaced relation on the outside 35 of the end-gate, diverging chute members leading from the head of said conveyer to said fans so as to convey the material from said conveyer to said fans, and means for driving said fans and the conveyer.

40 6. In combination with an end-gate, a hopper mounted on the inside thereof, a conveyer connected to said hopper and discharging over the top of the end-gate, a plurality of distributing fans on the outside 45 of the end-gate, means for conveying the discharge of said conveyer to said fans, said fans each having a driving pulley, a driving pulley for said conveyer, a main driving pulley, said pulleys being located in alinement and operatively connected together, and a member adapted to be driven from the wheel of a vehicle and having connections with said main driving pulley.

7. In combination with an end-gate, a hopper mounted on the inside thereof, a conveyer connected to said hopper and discharging over the top of the end-gate, a plurality of distributing fans on the outside of the end-gate, means for conveying the discharge of said conveyer to said fans, said fans each having a driving pulley, a driving pulley for said conveyer, a main driving pulley, said pulleys being located in alinement and operatively connected together,

and a member adapted to be driven from the wheel of a vehicle and having connections with said main driving pulley, said connections including a friction clutch.

48. In combination with an end-gate, a hopper mounted on the inside thereof, a conveyer connected to said hopper and discharging over the top of the end-gate, a plurality of distributing fans on the outside of the end-gate, means for conveying the discharge of said conveyer to said fans, said 70 fans each having a driving pulley, a driving pulley for said conveyer, a main driving pulley, said pulleys being located in alinement and operatively connected together, and a member adapted to be driven from the wheel of a vehicle and having connections with said main driving pulley, said connections including a friction clutch, and means for adjusting said friction clutch and said member.

85 9. In combination with an end-gate, a hopper mounted on the inside thereof, a conveyer receiving the discharge from the hopper and discharging over the top of the end-gate, a plurality of distributing fans 90 mounted on the outside of the end-gate, means for conveying the discharge of the hopper to said fans, a vertical shaft for driving said conveyer, having a pulley at its lower end, a pulley for driving each fan 95 and a main driving pulley, all of said pulleys being arranged in alinement and having operative connection with each other, a vertical shaft connected to said main driving pulley and having operative connection with a horizontal shaft, a member on said horizontal shaft adapted to be driven from the wheel of a vehicle, a friction clutch having connection with said member and adapted to operatively connect said member 100 to said horizontal shaft.

10. In combination with an end-gate, a hopper mounted on the inside thereof, a conveyer receiving the discharge from the hopper and discharging over the top of the 110 end-gate, a plurality of distributing fans mounted on the outside of the end-gate, means for conveying the discharge of the hopper to said fans, a vertical shaft for driving said conveyer, having a pulley at 115 its lower end, a pulley for driving each fan and a main driving pulley, all of said pulleys being arranged in alinement, said main driving pulley being mounted on the lower portion of a vertical shaft, a gear on the upper portion of said vertical shaft, a horizontal shaft having a gear meshing with said gear on said vertical shaft, a member loosely mounted on said horizontal shaft adapted to be driven from the wheel of a vehicle, 120 and a clutch member adapted to operatively connect said member with said horizontal shaft.

11. In combination with an end-gate, a hopper mounted on the inside thereof, a conveyer receiving the discharge from the hopper and discharging over the top of the 5 end-gate, supporting members secured to the outside of said end-gate and having spaced bracket members, a vertical shaft mounted in each pair of spaced bracket members, a distributing fan and a driving 10 pulley on each vertical shaft, an additional vertical shaft extending to the upper end of said conveyer and having driving means thereon for driving said conveyer and having a pulley on its lower end in alignment with said first mentioned pulleys, a main 15 driving pulley and means for driving said main driving pulley from the wheel of a vehicle.

BENJAMIN M. STEELE.
